[57] CLAIM

The ornamental design for an outdoor lighting fixture, as
shown and described.

DESCRIPTION

FIG. 1 is a perspective view of an outdoor lighting fixture
showing my new design;

FIG. 2 is a front elevational view of the lighting fixture;
FIG. 3 is a right elevational view of the lighting fixture, the
left elevational view being identical;

FIG. 4 is a rear elevational view of the lighting fixture;
FIG. 5 is a top plan view of the lighting fixture; and,
FIG. 6 is a bottom plan view of the lighting fixture.

The broken lines showing the lighting fixture shades are for
illustrative purposes.
